Patented Aug. 16, 1921.

UNITED STATES PATENT OFFICE.

MICHAEL J. LEAHY, OF PHILADELPHIA, PENNSYLVANIA.

WINDOW-VENTILATOR.

1,388,050.

Specification of Letters Patent. Patented Aug. 16, 1921.

Application filed April 10, 1920. Serial No. 372,865.

To all whom it may concern:

Be it known that I, MICHAEL J. LEAHY, a citizen of the United States, residing at Philadelphia, in the county of Philadelphia and State of Pennsylvania, have invented new and useful Improvements in Window-Ventilators, of which the following is a specification.

This invention relates to window ventilators, and comprehends a construction which is susceptible of use during rainy weather.

The chief characteristic of the present invention resides in the provision of a ventilator which may be varied in size to accommodate itself to windows of different widths, and one which is mounted upon the window frame in a manner whereby it can be readily positioned thereon or removed therefrom as the occasion requires.

In the drawing forming part of this specification like numerals of reference indicate similar parts in the several views and wherein:

Figure 1 is a front elevation of the ventilator showing the same mounted upon the window casing.

Fig. 2 is a vertical sectional view taken on the line 2—2 of Fig. 1.

Fig. 3 is a horizontal sectional view taken on the line 3—3 of Fig. 1.

Fig. 4 is a perspective view of the ventilator removed from the window.

Fig. 5 is a fragmentary perspective view of the modified form of the invention.

The ventilator forming the subject matter of my invention is made of two sections 10 and 11 respectively, each of which is identical in construction with the other. Each section comprises a top and an end wall 13, the top wall of the section 10 being slightly wider than the corresponding wall of the section 11 and formed with grooves 14 which slidably receive the adjacent edges of the section 11. In this manner, the sections 10 and 11 may be adjusted toward and

away from each other, so that the ventilator as an entirety can accommodate itself to windows of different widths. The outer edge of each section is formed with tongue and grooves 16 and 17 respectively for interfitting engagement with the tongue and groove 18 and 19 respectively of the window casing A. In applying the ventilator to a window, the sections can be moved toward each other and the ventilator placed between the sides of the window casing, after

which the sections can be moved away from each other until the tongue and grooves 16 and 17 respectively of the ventilator are fitted within the tongue and grooves of the window casing. When so positioned upon the window, the top wall 12 of the ventilator projects outwardly and downwardly an appreciable distance beyond the window casing thus permitting the use of the ventilator during rainy weather. The end wall 13 of each section is provided with a slot 20 which receives a pin or screw eye 21 projecting from the adjacent side of the window casing. The pin or screw eye 21 supports the ventilator upon the window casing as will be readily understood. The ventilator can be readily and easily removed from the window when desired, by bringing the sections 10 and 11 toward each other disengaging the sections from the window casing as well as from the pin or screw eye 21. The device is extremely simple in construction and can be manufactured and sold at a nominal cost.

In Fig. 5 I have illustrated a modified form of the invention, wherein one of the sections indicated at 11^a is of the same cross sectional configuration as the section 11 of the preferred form of the invention. The device shown in Fig. 5 varies from the preferred form in that the end wall 13^a forms an integral part of the section 11^a, the body of this section being bent upon itself at one end as shown so as to dispose the end wall 13^a in the same relation to the section as the end wall 13 of the preferred form of the invention. The section 11^a is formed with the tongue and groove 16^a and 17^a respectively in interfitting engagement with the tongue and groove of the window casing, while the end wall 13^a is formed with the slot 20^a to receive the pin or screw eye 21 which projects from the adjacent side of the window casing.

While I have shown and described what I consider the preferred embodiment of the invention, I desire to have it understood that I do not limit myself to any details of construction, inasmuch as such changes may be resorted to when desired as fall within the scope of what is claimed.

Having thus described my invention what I claim as new is—

1. A window ventilator comprising slidably associated sections, each section including an end wall disposed inwardly of the

outer end of the body of the section, and having an elongated slot, the projecting end portion of said section being formed to provide tongue and grooves for interfitting engagement with the tongue and grooves of the window casing, and means for holding the ventilator in position upon the window.

2. A window ventilator comprising two sections, one section terminating to provide 10 channels to slidably receive the other sec-

tion, an end wall on each section and arranged inwardly of the outer end thereof, each end wall having an elongated slot, the portion of the section projecting beyond the end wall being formed to provide tongue and grooves for interfitting engagement with the tongue and grooves of the window casing, and means for holding the ventilator in position upon the window.

MICHAEL J. LEAHY.
